UNITED STATES PATENT OFFICE.

PONTUS OSTENBERG, OF SAN JOSE, CALIFORNIA.

PUMP.

Application filed November 29, 1924. Serial No. 752,982.

To all whom it may concern:

Be it known that I, PONTUS OSTENBERG, a citizen of the United States, and a resident of San Jose, in the county of Santa Clara and State of California, have invented certain new and useful Improvements in Pumps, of which the following is a specification.

This invention relates particularly to deep well centrifugal pump structures.

In the present state of the art of deep well pump construction, when repair or replacement of any portion of the driving shaft or bearings therefor between the pump bowls and the top of the well becomes necessary, it is necessary to pull the entire pump from the well to effect such repairs or replacements.

It is the object of the present invention to provide a means whereby the pump shaft and its bearings may be separated from the pump proper at a suitable point above the uppermost bowl, and removed from the well and replaced therein without removing the pump bowls or impellers or detaching them from their supports, or otherwise materially disturbing their normal arrangement.

It is another object of the invention to provide a means of the character indicated that may be effectively and easily operated from the top of the well, and that will be economical to manufacture, simple in form and construction, of few parts, and highly efficient in its practical application.

In the drawings:—

Figure 1 is a vertical transverse section through a pump embodying my invention, parts broken away.

Figure 2 is an enlarged view of that portion of the pump structure shown in Figure 1 which embodies the principal features of the invention, partly in section and partly in elevation.

Figure 3 is an enlarged section on line 3—3 of Figure 1.

Referring more particularly to the drawing, I show at 1 a pump head with a discharge at 3, a pulley at 4, a drive shaft at 5 and a tubular enclosure for the shaft 5 at 6.

The tubular enclosure 6 is supported in head 1 by means of a nut 7, and a discharge casing 2 is suspended from head 1 by being threaded into the same as indicated at 8.

I prefer to join the shaft sections by threading them into couplings as shown at

9, these couplings rotating within the tube 6 which acts as a bearing therefor. The several tube sections are joined by couplings 10 into which they are threaded and secured against separating when the tube is revolved 60 backwardly by set screws 11.

From the lower end of casing 2 is suspended the pump bowl structure 13, including impeller 14 on shaft 5, and a bearing 15 supported in bowl 13 by webs 16.

On the upper surface of impeller 14 are formed radially arranged ribs 17, and in the lower surface of bearing member 15 are formed radially arranged grooves 18 adapted to receive ribs 17.

The upper end of bearing member 15 is threaded to engage the lower end of tube 6 as shown at 19.

The lower end of the tube 6 has a socket member 20 fixedly positioned therein, this 75 socket in the present case having a hexagonal inner surface as shown at 21 and provided at its lower end with an inwardly extending flange 22.

The shaft 5 is divided just above bearing 15 but normally joined to operate as a unit by coupling 23 into which the two parts are threaded, the exterior surface of coupling 23 being hexagonal in form as at 24, and of such a size that the member 20 will slide 80 thereover and engage the same.

At 25 I show several webs carried by tube 6 and extending radially outward to slidably engage casing 2 adjacent to and preferably between the coupling 23 and the upper 90 end of bearing member 15.

Assuming the pump structure to be formed and installed as hereinbefore described, if on account of the breaking of the shaft 5 or for any other reason, it is desired 95 to remove the shaft from the well, the following steps are taken.

First, the tube 6 is rotated backwardly until it is unscrewed from bearing member 15 at 19. This may be done without separating the several tube joints because they are held in couplings 10 by set screws as described.

The tube having been loosened from the bearing it is raised a distance until the member 20 passes over coupling 23 on shaft 5, the flange 22 of said member 20 engaging the lower end of said coupling and thereby raising the shaft 5 and the parts carried thereby. The shaft of course can be raised 105 110 115

but a little way at this time, or until it is stopped by the engagement of the impeller 14 with the bottom of bearing member 15. When this occurs the webs 17 on the top of 5 impeller 14 engage grooves 18 in the bottom of member 15.

When the tube 6 is again rotated backwardly the engagement of member 20 with coupling 23 causes the shaft 5 to rotate 10 backwardly. But since the lower end of shaft 5 cannot rotate on account of the engagement between the impeller and the bearing member, it must necessarily unscrew in the coupling 23.

15 This separation at points 19 and 23 permits withdrawal of the entire tube 6, shaft 5 (above bearing 15) and parts mounted thereon, without disturbing the discharge casing or any of the bowls or impellers 20 mounted therein.

When the shaft and tube are again inserted in the pump the webs 25 first engage the casing 2 and center it over the bearing 15. As the parts are lowered and 25 rotated forwardly they are screwed into position and the pump is again ready to be operated.

The tube 6 really forms the handle to a 30 socket wrench normally held in a fixed position by screwing on to the bearing 15 at 19, but used for the dual purpose of unscrewing and separating the shaft 5 and raising the same to the surface of the ground after it has been detached from bearing member 15.

It is to be understood, of course, that 40 while I have herein shown and described one specific embodiment of the invention, changes in form, construction and method of operation may be made within the scope of the appended claims.

I claim:

1. In a deep well pump, a discharge casing, a bowl connected thereto, an impeller 45 in said bowl; a jointed shaft carrying said impeller, a coupling connecting the two shaft sections, a tube enclosing said shaft and engaging said bowl, means carried by the tube adapted to engage said coupling 50 and disengage the same from one shaft section.

2. In a deep well pump, a discharge casing, a bowl connected thereto, an impeller in said bowl, a jointed shaft carrying said 55 impeller, a coupling connecting the two shaft sections, a tube enclosing said shaft and engaging said bowl, means carried by the tube adapted to engage said coupling and disengage the same from one shaft section, and supporting means for the disengaged shaft section carried by said tube.

3. In a deep well pump, a discharge casing, a bowl connected thereto, an impeller in said bowl, a jointed shaft carrying said 60 impeller, a coupling connecting the two

shaft sections, a tube enclosing said shaft, and means carried by the tube adapted to engage said coupling and disengage the same from one shaft section.

4. In a deep well pump, a discharge casing, a bowl connected thereto, an impeller in said bowl, a shaft carrying said impeller and separable at a point a distance above said bowl, a coupling therefor, a bearing for said shaft above said impeller, a tubular 75 column enclosing said shaft and normally engaging said bearing, means carried by said column adapted to engage and unfasten said coupling when disengaged from said bearing, and means for supporting the 80 upper portion of the disengaged shaft carried by said column.

5. In a deep well pump, a discharge casing, a bowl connected thereto, an impeller in said bowl, a shaft carrying said impeller 85 and separable at a point a distance above said bowl, a coupling therefor, and means for unfastening said coupling extending to the top of the well, and means carried by said unfastening means adapted to engage 90 said coupling whereby to lift the upper separated shaft portion.

6. In a deep well pump, a discharge casing, a bowl connected thereto, an impeller in said bowl, a shaft carrying said impeller 95 and separable at a point a distance above said bowl, a coupling for the shaft portions, a bearing for the shaft below said coupling, a tubular column enclosing the shaft and having separable engagement 100 with said bearing, coupling unfastening means carried by said column and rendered operative after the separation of said column from said bearing, and means for preventing movement of the lower portion 105 of said shaft during said unfastening operation.

7. In a deep well pump, a discharge casing, a bowl connected thereto, an impeller in said bowl, normally inoperative interlocking means between said impeller and bowl, a separable shaft carrying said impeller, a coupling therefor, a coupling unfastening device operable from the top of the well, and means carried by said device 110 adapted to render said interlocking means between said impeller and bowl operative 115 prior to the unfastening of the coupler.

8. In a deep well pump, a discharge casing, a bowl connected thereto, an impeller in said bowl, normally inoperative interlocking means between said impeller and bowl, a separable shaft carrying said impeller, a coupler nut into which said shaft portions are threaded, a bearing for the 125 shaft below said coupling, a tubular column threaded into said bearing in the same direction as the threaded connection between the shaft and coupler, a socket carried by said column adapted to engage said coupler 130

to unscrew the same from the lower portion of the shaft, and a flange carried by said socket adapted to engage and lift said coupler and shaft and render said interlocking means operative.

9. In a deep well pump, a discharge casing, a bowl connected thereto, an impeller

in said bowl, separable shaft sections carrying said impeller, a tube enclosing said shaft sections, and means inserted between said tube and shaft sections and operated by movement of said tube for separating said shaft sections.

PONTUS OSTENBERG.
